UNITED STATES PATENT OFFICE.

FREDERICK SKINNER, OF BARRANCO, PERU, ASSIGNOR OF ONE-HALF TO ALL AMERICA CABLES, INC., OF NEW YORK, N. Y., A CORPORATION OF NEW YORK.

AUTOMATIC TRANSMITTER.

Application filed April 22, 1921. Serial No. 463,552.

To all whom it may concern:

Be it known that I, FREDERICK SKINNER, a subject of the King of Great Britain, residing at Barranco, Peru, have invented certain new and useful Improvements in Automatic Transmitters, of which the following is a full, clear, and exact description, such as will enable others skilled in the art to which it appertains to make and use the same.

This invention relates to transmitters and more particularly to automatic telegraphic transmitters of the type employing a perforated tape.

It is one of the objects of the invention to provide an improved transmitter of the class mentioned whereby greater uniformity and regularity of movement of the transmitting elements are accomplished.

Another object is to provide in a transmitter of the class mentioned, improved driving means for the transmitting elements, operating positively and with precision.

Another object is to provide in an automatic transmitter improved means for accuracy and delicacy of adjustment of the contact elements whereby adjustments for variations in line conditions are accomplished.

Other objects will be in part obvious and in part pointed out hereinafter in connection with the detailed description.

The invention accordingly consists in the features of construction, combinations of elements and arrangement of parts which will be exemplified in the construction hereinafter set forth, and the scope of the application of which will be indicated in the following claims.

Heretofore it has been common practice to employ automatic telegraphic transmitters with rotary motors for operating the same. Such a motor drive has proved unsatisfactory in many installations on account of objectionable irregularities in the operation of the transmitter. The present invention largely avoids the objections noted by providing an improved drive in the form of a step-by-step motor preferably comprising an electro-magnet provided with a pivoted armature connected to impart intermittent movement to the tape and transmitting

parts, the magnet being connected for intermittent energization by any approved means.

In the preferred embodiment of the invention disclosed in the accompanying drawings,

Figure 1 is a sectional view of the transmitter, taken approximately on the line 1—1 of Fig. 2, showing in side elevation the driving motor and transmitter elements;

Fig. 2 is a top plan view of the same;

Fig. 3 is a simplified diagrammatic view of a system employing the improved automatic transmitter;

Fig. 4 is a view of a portion of the tape employed in the transmitter;

Fig. 5 is a top plan view showing a modification of the invention;

Fig. 6 is a perspective view of the same, and

Fig. 7 is a fragmentary detail sectional view taken approximately on the line 7—7 of Fig. 5.

Referring to the drawing, and first to the embodiment of Figures 1 and 2, a pair of base plates 1 and 2 are provided spaced apart by bars 3 and preferably carrying suitable terminal binding screws (not shown) for attaching the terminal leads. Pivoted contact rocker arms 4 and 5 are mounted on an insulating block 6 secured to the inner face of plate 2 carrying at one end contacts 7

cooperating with stationary contacts 8 on supporting blocks 9 and 10 also mounted on said insulating block. To the opposite ends of these contact arms are pivotally connected upright controlling rods 11 and 12 having insulated joints 13 intermediate their ends and adapted to cooperate at their upper ends with a perforated tape 14. The tape may be supported and guided in any desirable manner by horizontal plates carried by the base plates, one of these plates 15 being indicated in dotted lines in Fig. 1.

A rotary shaft 17 is mounted in plate 1 and a bracket 18 secured to said plate, carrying at one end thereof a toothed sprocket wheel 19, the teeth thereof extending through the plate 15 into position to engage in a series of central openings 14^a in the tape. The shaft also carries a driving ratchet wheel 20, and a holding ratchet and

55

pawl 21 preventing retrograde movement of the shaft. The control rods 11 and 12 are spaced at opposite sides of the sprocket wheel 19, their upper ends extending through openings in plate 15 in alignment with the series of openings 14^b and 14^c in the tape 14 in a manner understood in the art.

The driving motor for the tape and transmitter contacts preferably comprises an electro-magnet 22 suitably carried by a plate 23, being longitudinally adjustable by means of a threaded rod 24 and nut 25, the rod being attached to the magnet and extending through the plate 23. Adjustment of the nut will positively move the magnet in one direction, this movement being opposed by a spiral spring 26, tensioned between the magnet and plate 23 and tending to separate the same. The armature 27 is mounted on a pivoted arm 28 carrying at its upper end a spring pressed pawl 29 positioned to cooperate with the ratchet wheel 20. The movement of the armature toward the core is opposed by a spring 30 having an adjustable tensioning screw 31, and the throw of the arm is adjusted by means of a screw 32 on one side thereof. It is obvious that a similar adjusting screw may be provided on the opposite side, if desired.

The contact arms are biased to contacting position as by springs 33 and are provided at their ends with rollers 34 and 35 of agate or similar material. Inclined adjustable screws 36 on arm 28 are arranged to contact with these rollers to separate contacts 7 and 8 when the armature moves away from the magnet and to release the same to the influence of springs 33 and tape 14 when the armature moves in the opposite direction under magnet energization. When the magnet is energized it will be obvious that contact arm 4 or 5 will operate to close its contact and send an impulse over the line providing there is an opening in the tape in alignment with the end of the corresponding rod 11 or 12. If there is no tape opening in alignment with either of the rods 11 or 12 the contacts will be held apart by engagement of the rods with the body of the tape. It will also be clear that the interval of contact relative to the interval of separation of the contacts 7 and 8 may be readily adjusted by means of screws 36. This is an advantageous feature since it is desirable to secure relatively long intervals of contact for satisfactory operation of a distant receiver where the line resistance is high or insulation low, or where other conditions exist giving rise to excessive current leakage.

Fig. 4 of the drawing shows a typical installation including the improved transmitter T and cable sounder S with electrical connections 38, 39 and 40 therebetween. A source of energy B is also provided and

the electrical conductors are connected to receiver magnets 41 and 42 one or the other receiving an impulse depending on which contact is closed at the transmitter. It will be understood that the impulse sent out by the closing of one of the transmitter contacts is distinguishable at the sounder as a dot while that sent out by the other contact is distinguishable as a dash so that signals can be sent out in combinations of dots and dashes in the Morse code or in any other code in a manner well known in the art. The terminals 43, 44 and 45 of the sounder are arranged to be connected to the line or cable, to earth, and to a source of energy, respectively.

Intermittent energization of the magnet 22 is accomplished by means of a circuit interrupter I connected to a source of energy B' and to the terminals of said magnet. This interrupter may be of any approved form, but is preferably of the Gulstad type delivering impulses timed by the resistances R and R' and condenser C in a manner well known in the art. It is obvious that the resistances or the condenser or both resistances and condenser may be adjustable so as to vary the frequency of the impulses delivered to the magnets. Reciprocating movement of any desired frequency is thus imparted to the pivoted arm 28 and to the contact arms 4 and 5 while intermittent movement is imparted to the tape 14.

The operation of the improved transmitter is embodied in the foregoing description and reiteration thereof is believed to be unnecessary to a complete understanding by those skilled in the art.

The embodiment of Figs. 5, 6 and 7 is similar to that of Figs. 1 and 2 and corresponding references with primes are employed to designate corresponding parts. Some parts, however, vary in construction and will be described in detail. In this embodiment contact rocker arms 4' and 5' are mounted on an insulating block 6' on the outer face of base plate 2 and are urged toward contacting positions by springs 33'. As shown in Fig. 7, the pivoted arm 28' is provided with a laterally extending arm 50 secured thereto carrying pivotally at its free end a link 51 threaded at its upper end for the reception of an adjusting nut 51' and extending through an opening in an arm 52 of a frame 53 pivoted at shaft 54 to the base plates 1 and 2. This frame is provided with arms 55 and 56 carried by the pivot shaft 54 supporting at their free ends a transverse rod 57 having an extending portion passing through an opening in plate 2 and overlying the contact arms in position to restrain upward movement thereof.

As shown in Fig. 6 the tape 14 passes over the surface of a plate 58 carried by uprights 59 on one of the base plates and

having openings for the reception of the sprocket wheel 19' on the end of shaft 17' which, in this case, extends through an opening in the base plate 2. As in the first embodiment, contact controlling rods 11' and 12' are arranged at opposite sides of the sprocket wheel extending through openings in plate 58 into position to cooperate with the tape. A hinged guide block 60 may be arranged to swing down over the tape to confine and guide the same in proper position. Also an adjusting block 61 is slidably mounted on the underside of plate 58 being provided in its forward edge with notches to receive the control rods for bringing them adjustably into proper alignment with the tape and sprocket wheel. The control rods are pressed into engagement with the block 61 by springs 62 and the block is adjustable by means of a threaded rod 61' attached thereto passing through an opening in upright 59 and provided with an adjusting nut 64. A spiral spring 65 is stressed between the adjusting block and upright tending to separate the same.

The operation of this modification is similar to that of Figs. 1 to 3 and will be obvious from the above description. However, it will be noted that the relative intervals of the completed and interrupted circuit are varied by adjusting the nut 51' on the end of link 51 thus varying the interval of restraint exerted on contact rocker arms 4' and 5' by engagement therewith of the projecting end of rod 57. As the armature is attracted it will be noted that the arm 50 and link 51 rise leaving the rod 57 free to be raised by the contact arms acting under the influence of the tape and their respective springs 33'.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described, and all statements of the scope of the invention which, as a matter of language, might be said to fall therebetween.

Having described my invention, what I claim as new and desire to secure by Letters Patent is:

1. In a transmitter, in combination, a rocking contact bar for controlling the transmitter contacts to produce line impulses, a controlling rod pivoted to said bar, a controlling tape adapted to cooperate with said bar to control said contacts, a reciprocating motor for driving said contact bar

and said tape in synchronism therewith, means for effecting uninterrupted operation of said motor, and an adjusting mechanism connected between said motor and said contact bar for varying the relative periods of completed and interrupted circuits.

2. In a transmitter, in combination, a rocking contact bar for controlling the transmitter contact to produce line impulses, a controlling rod pivoted to said bar, a controlling tape adapted to cooperate with said bar to control said contact, means to normally bias said controlling rod into position to cooperate with said tape, an electric motor with an electro-magnet and a reciprocating armature for intermittently advancing said tape, means operatively connected to said armature and to said contact bar for restraining said controlling rod from cooperation with said tape in opposition to said biasing means coincident with a tape advancing stroke of the motor, and for withdrawing said restraint coincident with a reverse stroke, and an adjusting means positioned in the connection between said armature and contact bar to vary the interval of contact.

3. In a transmitter, in combination, a rocking contact bar for controlling the transmitter contact to produce line impulses, a controlling rod connected to said bar, a controlling tape adapted to cooperate with said bar to control said contact, means to normally bias said controlling rod into position to cooperate with said tape, an electric motor with an electro-magnet and a reciprocating armature for intermittently advancing said tape, and means operatively connected to said armature and to said contact bar for restraining said controlling rod from cooperation with said tape in opposition to said biasing means coincident with a tape advancing stroke of the motor, and for withdrawing said restraint coincident with a reverse stroke, and an adjusting means positioned in the connection between said armature and contact bar to vary the interval of contact, said adjusting means including a roller and an adjustable member cooperating therewith.

4. In a transmitter in combination, a rocking contact bar for controlling the transmitter contact to produce line impulses, a controlling rod pivoted to said bar, a controlling tape adapted to cooperate with said bar to control said contact, a spring to normally bias said controlling rod into position to cooperate with said tape, an electric motor with an electro-magnet, and a reciprocating armature for intermittently advancing said tape, a spring operatively connected to said reciprocating armature for restraining said controlling rod from cooperating with said tape in opposition to said biasing means coincident with a tape advancing stroke of the motor, and for withdrawing

said restraint coincident with a reverse stroke, and means for adjusting the relative positions of said magnet and armature.

5. In a transmitter, in combination, a rocking contact bar for controlling the transmitter contact to produce line impulses, a controlling rod pivoted to said bar, a controlling tape adapted to cooperate with said bar to control said contact, a spring to normally bias said controlling rod into position to cooperate with said tape, an electric motor with an electro-magnet and a reciprocatory armature for intermittently advancing said tape, a spring operatively connected to said reciprocatory armature for restraining said controlling rod from cooperating with said tape in opposition to said biasing means coincident with a tape advancing stroke of the motor, and for withdrawing said restraint coincident with a reverse stroke, means for adjusting the relative positions of said magnet and armature, and an adjusting means in the connection between said armature and contact bar to vary the interval of contact, said last mentioned adjusting means including a roller and an adjustable member cooperative therewith.

6. In a transmitter, in combination, a rocking contact bar, a tape for controlling said contact bar, a motor for intermittently advancing said tape, said motor including a magnet and a reciprocatory armature, an adjusting screw located externally of said transmitter for adjusting the respective positions of said magnet and armature, a spring for exerting a force on said armature in opposition to the force exerted thereon by said magnet, and an adjusting means operable externally of the transmitter for adjusting the tension of said spring.

7. In a transmitter, in combination, a rocking contact bar, a tape for controlling said contact bar, a motor for intermittently advancing said tape, said motor including a magnet and a reciprocatory armature, an adjusting screw located externally on said transmitter for adjusting the relative positions of said magnet and armature, a spring for exerting a force on said armature in opposition to the force exerted thereon by said magnet, an adjusting means operable externally of the transmitter for adjusting the tension of said spring, and a control rod connected to said contact bar and cooperable with said tape.

8. In a transmitter, in combination, a circuit interrupting means including a rocking contact bar, a motor having a reciprocatory armature for driving said contact bar, and a driving connection between said armature

and contact bar including a roller and an adjustable screw contacting therewith.

9. In a transmitter, in combination, a circuit interrupting means including a rocking contact bar, a motor having a reciprocatory armature for driving said contact bar, a driving connection between said armature and contact bar including a roller and an adjustable screw contacting therewith, a controlling tape, and a selective controlling rod pivoted to said contact bar and cooperable selectively with said perforated tape.

10. In a transmitter, in combination, a rocking contact bar, a tape for controlling said contact bar, a motor for intermittently advancing said tape and including an electro magnet and a reciprocatory armature, a ratchet wheel and a pawl pivoted directly to said reciprocatory armature and cooperating with said ratchet wheel to effect intermittent advancement of the tape.

11. In a transmitter, in combination, a rocking contact bar, a controlling rod pivotally connected to said contact bar, a tape for controlling said contact bar through said controlling rod, a motor for intermittently advancing said tape and operating said contact bar and including an electro magnet and a reciprocatory armature, a ratchet wheel, a pawl pivoted directly to said armature and cooperating with said ratchet wheel to effect intermittent advancement of the tape, and an operating connection between said armature and said rocking bar and including a roller and contacting adjustable screw to vary the relative periods of make and break of the transmitter contacts.

12. In a transmitter, in combination, a rocking contact bar, a tape for controlling said contact bar, a motor for intermittently advancing said tape including an electro-magnet and a reciprocatory armature, means for mounting said electro-magnet for movement with reference to said armature, an adjusting means operable externally of the transmitter for effecting adjustment of said electro-magnet, a spring connected to said armature for exerting a force thereon in opposition to the force exerted by said electro-magnet, and being adjustable externally of the transmitter and an adjusting means connected with said armature to vary the period of contact of the transmitter.

In testimony whereof I affix my signature, in the presence of two witnesses.

FREDERICK SKINNER.
